UNITED STATES PATENT OFFICE.

FRED E. HOWARTH, OF UTICA, NEW YORK.

DESIGN FOR A LIGHTING-FIXTURE.

48,378.

Specification for Design.

Patented Jan. 4, 1916.

Application filed September 30, 1915. Serial No. 53,469. Term of patent 7 years.

To all whom it may concern:

Be it known that I, FRED E. HOWARTH, a citizen of the United States, residing at Utica, in the county of Oneida and State of New York, have invented a new, original, and ornamental Design for a Lighting Fixture, of which the following is a specification, reference being had to the accompanying drawing, forming part thereof.

The figure is an elevation of a lighting fixture, showing my new design.

I claim:—

The ornamental design for a lighting fixture, as shown.

FRED E. HOWARTH.

Witnesses:

JACK E. SCHAFER,
J. EDW. SCHAFER.
